(57) **CLAIM**

The ornamental design for a side plate for rack, as shown and described.

DESCRIPTION

FIG. 1 is a front perspective view of a side plate for a rack showing our new design;

FIG. 2 is a front view thereof;

FIG. 3 is a top view thereof;

FIG. 4 is a rear view thereof;

FIG. 5 is a side view thereof, the opposite side being identical;

FIG. 6 is a bottom view thereof;

FIG. 7 is an enlarged view of the central portion of the front side thereof;

FIG. 8 is a side view of the portion of FIG. 7, the opposite side being identical; and,

FIG. 9 shows a perspective view thereof, with environmental material shown in broken lines.

The broken line showing of environmental material is for illustrative purposes only and forms no part of the claimed design.
